REGISTER CONTROL MECHANISM

Francis J. Rouan, Stamford, Conn., assignor to
 Pitney-Bowes Postage Meter Co., Stamford,
 Conn., a corporation of Delaware

Application January 11, 1941, Serial No. 374,076

4 Claims. (Cl. 235—138)

This invention relates to the control of an ascending and descending register and more particularly to a delayed transfer associated therewith.

One object of the invention is to provide means whereby actuation of two independent register units and the operation of a delayed transfer is provided during one cycle of a register actuator.

It is another object of the invention to provide a delayed transfer of compact and novel design which is especially capable of operation at high speed.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein:

Fig. 1 is a cross-sectional view through a totalizer and transfer mechanism including the actuator drive therefor;

Fig. 2 is a part elevational and part sectional view, showing the drive means for a totalizer actuator, including a Geneva drive for the actuation of transfer mechanism;

Fig. 3 is a detailed elevational view with parts in section, taken in the direction of the arrow 3 on Fig. 1 and showing part of the transfer actuator mechanism; and

Fig. 4 is a cross-sectional view taken on the line 4—4 of Fig. 3 and showing particularly the transfer pawls and actuating transfer dogs.

Referring to the drawings in detail, the register comprises two distinct but identical units, one indicated generally at "A" which will be referred to as the ascending register unit and the other indicated at "D," which will be referred to as the descending register unit. In view of both of said register units being identical, it will be necessary to only describe one unit where the parts of each are identical, and for this purpose the ascending unit A will be described. Such parts in the unit D, which are a duplicate of those of the unit A, will have the same reference characters applied thereto, but with the exponent *d* added, for the proper identification of same.

Referring therefore to the unit A, the same comprises a plurality of indicator wheels 10, each wheel of which has a pinion 11 fixed thereto,

also a transfer dog 12. Meshing with the pinion 11 is an intermediate pinion 13. The indicator wheels 10 are carried by a shaft 14 and the intermediate pinions 13 are carried by a shaft 15. Meshing with the intermediate pinion 13 is another pinion 16 on a shaft 17, and fixed to said pinion 16 is a driven gear 18.

The gear 18 and its companion gear 18*d*, of the unit D, are arranged in close proximity to one another, and each is adapted to be driven by a segmental actuator 19. Said actuator 19 is of the variable tooth or mutilated gear construction, having a variable number of teeth ranging from 1 to 9 teeth and is adapted for adjustment relative to the gears 18, 18*d* to drive said gears a distance equal to from one up to nine teeth, in accordance with the position at which the variable toothed actuator 19 is adjusted. An actuator gear of this character is normally adapted to be adjusted by suitable manual means, but since the adjustment forms no part of the present invention, the same is not shown.

Transfer means is provided, as best shown in Figs. 3 and 4. Here again elements are provided which, although not being identical in structure, are identical in their operating characteristics for the control of the ascending and descending registers. Description therefore will be directed to the transfer means which is associated with the ascending totalizer, and said portions which are similar in the descending transfer means will bear identical reference characters but with the exponent *d* added thereto. Referring particularly to the transfer pawls of the register unit A, the same comprises a longitudinally slideable member 22, which has an elongated opening 23 therein, and is normally supported at each end thereof. One point of support is provided by means of a projecting finger 24, which bears against a supporting surface 25 of a support bar 26. The opposite end of said transfer pawl 22 has a slot 27 therein, and is adapted to be supported by a rod 28 which extends therethrough. Also at the latter end of the pawl 22 is a projecting finger 31, which normally lies in the path of the transfer dog 12. When the transfer dog completes a full revolution, which occurs at the time indicator wheel passes from a "9" to a "0" position, the said dog will engage the finger 31 of the transfer pawl and move said pawl longitudinally along its supporting members 26 and 28. When the transfer dog 22 is moved, it is retained in its adjusted position by means of a detent pawl 33. Said pawl 22

is further provided with a bent lip portion 32 which lip forms a cam surface and is adapted to deflect a transfer actuator member to a transfer actuating position.

The transfer actuator, which is best shown in Figs. 2 and 3, comprises a ring 34, which ring has a tooth 35 projecting beyond the edge thereof. Said ring is confined within a cup-shaped member 36 and is normally urged against the inner wall thereof by means of a spring 37. A cap 38 is provided to close the open end of the cup-shaped member. Said cup member is fixed to a driven shaft 39 and has a clearance opening 41 through the wall thereof, through which the tooth 35 projects. Upon rotation of the shaft 39, the tooth 35 will be moved through a circumferential path, which path is in alignment with that of the cam surface of the lip 32, on the transfer pawl 22. When the transfer pawl 22 is in its lowermost position as shown in Fig. 4, the tooth 35 will ride clear of the lip portion 32. When, however, the said transfer pawl 22 is adjusted to a transfer position by the engagement of the dog 12 with the finger 31, as described above, the said lip portion 32 will project into the path of the tooth 35. The said tooth 35 will engage the lip 32 and be cammed sidewardly into the path of the intermediate pinion 13, to thus engage and drive said pinion 13 the distance of one tooth and advance the indicator wheel 10 of next higher order one digit.

One transfer actuator is provided for each indicator wheel and the several actuators are arranged on the shaft 39 in a staggered relation, as shown in Fig. 2, so that each transfer is effected at a different period during the revolution of the driven shaft 39.

Said transfer mechanism controls the transfer of each of the two register units during one cycle or revolution of the variable toothed actuator gear 19. To permit the said actuator gear 19 to complete its drive of the first register unit A through the driven gear 18, means is provided to withhold the drive of the transfer actuating mechanism until after the drive of the said unit A. Said means comprises a Geneva drive arm 42, which is carried by a shaft 40 and is driven from the main drive shaft 43. Said shaft 43 supports the variable toothed gear 19, and has a drive gear 44 fixed thereon which drives an intermediate gear 45 and gear 46, the gear 46 being rotatable with the Geneva drive arm 42. The arm 42 has a roller 47 thereon which is adapted to engage with the wall of a slotted end 48 of a Geneva member 49, after the gear 46 has rotated through approximately a full revolution. The ratio of the gearing 44-45 is 2 to 1, therefore, the gear 46 and arm 42 will rotate through two revolutions to the one revolution of the variable toothed gear 19. During the second revolution of the gear 46, the Geneva member 49 will move a mutilated gear 51 into engagement with a gear 53, which latter gear is driven with the gear 46 and arm 42. The drive of said gear 51, and the transfer actuator shaft 39, to which it is attached, is thus continued through a revolution to provide for the transfer operations in both of the register units A and B, in the manner described above.

As each of the teeth 35 of the transfer actuators completes a transfer, an overthrow preventing cam 54 which is positioned directly back of the tooth 35, will engage one end 55 of a lever 56, to rock said lever about a supporting shaft 57. A detent 58, formed as a part of the end 55,

will engage between the teeth of a star wheel 59 immediately after a tooth 35 completes a transfer to thereby prevent overthrow. The star wheel is fixed to the intermediate pinion 13 and thus chokes the rotation of the register indicator wheel 10. The same choke lever 56 performs a double duty in effecting a choke of each of the two register units A and B, there being an end 55d on the said lever 56 which is engaged by the choke arm 54 and a detent 58d which will engage the teeth of a star wheel 59d of the register unit D.

Choking of the indicator wheels is provided, after entry of an amount therein by the actuator 19, by means of a cam 61, which is adapted to engage the head 62 of a lever 63 and move said lever to a choking position to effect a choke at the instant the last tooth of the actuator 19 leaves the gear 18. A tail 64 projecting from the lever 63 has a pin 65 therein which is adapted to engage a tail 66 of a choke pawl 67. When the lever 63 is rocked by the cam 61, the pin 65 will rock the pawl 67 to move the detent portion 68 of said pawl into a choking position between the teeth of the pinion 11.

A similar choking arrangement is provided for the pinion 11d of the register D by the engagement of a pin 65d with the detent head 68d of detent lever 67d.

Restoring of the transfer pawls 22, which have been set in a transfer position, is effected by means of teeth 71 which contact with shoulder portions 72-72d on the transfer pawls 22-22d when a transfer has been completed.

Having described the invention, what is claimed is:

1. In mechanism of the character described, the combination with an ascending register and a descending register, including indicator wheels and drive gears for each register; of an actuator gear adapted to drive one then the other of the said drive gears of each register, delayed action transfer means associated with the register drive gears of the ascending register, delayed action transfer means associated with the register drive gears of the descending register, each of said transfer means being adapted to effect a transfer in the drive gears of the respective registers, means to drive the actuator gear, and means connected with the actuator gear drive to drive the transfer means after the actuator gear has completed its drive of one of the registers.

2. In mechanism of the character described, the combination with an ascending register and a descending register, including indicator wheels and drive gears for each register, of an actuator gear adapted to drive one then the other of the said drive gears of each register, delayed action transfer means associated with the register drive gears of the ascending register, delayed action transfer means associated with the register drive gears of the descending register, each of said transfer means being adapted to effect a transfer in the drive gears of the respective registers, means to drive the actuator gear, and a Geneva drive connected with the actuator gear drive to effect a drive of the transfer means after the actuator gear has completed its drive of one of the registers.

3. In a duo-register device including two sets of indicator wheels and a transmission drive for each indicator wheel; an actuator movable to drive first one transmission drive then the other, transfer dogs associated with each of the indicator wheels, transfer pawls having one of

their ends projecting in the paths of the transfer dogs and adapted for endwise adjustment when engaged by said dogs, the transfer pawls of one register crossing the transfer pawls of the other register, a shaft passing through clearance openings in said transfer pawls at the point of intersection of said pawls, and rotatable transfer actuating members carried by said shaft and having yieldable single toothed members adjustable into driving relation with the transmission drive of either register by the transfer pawls after any transfer dog moves an associated transfer pawl to a transfer position.

4. In a duo-register device including two sets of indicator wheels and a transmission drive for each indicator wheel; an actuator movable to drive first one transmission drive then the

other, transfer dogs associated with each of the indicator wheels, transfer pawls having one of their ends projecting in the paths of the transfer dogs and adapted for endwise adjustment when engaged by said dogs, means to support the pawls at the ends thereof, the transfer pawls of one register crossing the transfer pawls of the other register, a shaft passing through clearance openings in said transfer pawls at the point of intersection of said pawls, and rotatable transfer actuating members carried by said shaft and having yieldable single toothed members adjustable into driving relation with the transmission drive of either register by the transfer pawls after any transfer dog moves an associated transfer pawl to a transfer position.
